RADIO ANTENNA

Russell J. Scott, Kalamazoo, Mich., assignor to
 Shakespeare Products Company, Kalamazoo,
 Mich., a corporation of Michigan

Application May 28, 1945, Serial No. 596,127

1 Claim. (Cl. 287—58)

1 This invention relates to improvements in antennae, such as used for the transmission and/or reception of radiant energy, intelligence, etc., from and by radio transmitting and receiving apparatuses, particularly mobile types of radio transmitting and/or receiving sets as provided to automobiles, though adaptable to substantially all forms of land, marine and, in some instances, airborne vehicles.

An object of the invention is to provide a radio antenna of the telescopic collapsible type, which primarily, consists of a mast made up of an assembly of telescopically interengaged sections so constructed and relatively arranged as to afford materially improved electrical characteristics, similarly improved over-all mechanical construction, with coincidental features of rugged durability, solidity of construction and assembly stability of and between its movable parts, and proofing of the same against the deteriorating actions or effects of climatic conditions and/or elements.

It is also an important object of the invention to provide an antenna mast of the indicated character, wherein the telescopic mast sections or members will have portions thereof so frictionally interengaged as to positively ensure their collective and/or individual firm, though movable retention, in telescopically collapsed, distended or partially distended positions or relationships.

Yet another object of the invention is to provide the antenna mast sections or members with novel means which will effectually function to maintain firm, positive frictional, and movable and wiping electrical contact, therebetween, hence, preventing relative play, rattling or other vibratory movement between said mast members, and also, maintaining constant, positive electrical connection therebetween with resultant sustained and dependable operational efficiencies.

The invention also aims to provide a radio antenna of the collapsible mast type, wherein connection between the sections or members thereof is so effected and kept as to prevent the passage of moisture thereby into the receiving member or members, and so, prevent corroding, rusting and other deterioration of the housed portions when they are in telescopically collapsed, distended or partially distended relativity.

Heretofore, in the production of telescopic mast types of radio antennae, I am aware that consideration has been given to providing the sections thereof with frictional and other forms of

2 means for effecting movable mechanical and electrical interconnection therebetween. Such products have, however, not proven satisfactory because of, amongst other reasons, ineffectual mechanical holding or retention of the mast sections in telescopically collapsed, distended or partially distended relationships; the entrance of moisture between and into the tubular sections of the mast, thereby corroding, rusting or otherwise effecting parts deterioration of the unprotected or untreated mast sections when exposed to the elements, and detrimental and objectionable rattling or other vibratory motion between the mast sections, irrespective of their relative positioning, all of which are contributory to faulty electrical conductivity of the antenna.

The noted difficulties, as well as others, are eliminated by and through the use of my improved antenna.

20 Other objects of the invention will be in part obvious and in part pointed out hereinafter.

In order that the invention and its mode of operation may be readily understood by those skilled in the art to which it appertains, I have 25 in the accompanying drawings and in the detailed following description based thereupon, set out two embodiments of my invention.

In the drawings:

Figure 1 is a side elevation of my improved 30 mast radio antenna, showing the same in a telescopically collapsed position and mounted in a mounting bracket.

Figure 2 is an enlarged longitudinal section 35 through the improved antenna and the mounting bracket therefor, with parts of the antenna mast broken away.

Figure 3 is an enlarged fragmentary detail in 40 longitudinal section through the outer end of the innermost tubular member of the antenna mast, showing its connection with the mast rod section.

Figure 4 is a transverse section taken on the 45 line 4—4 of Figure 3, looking in the direction in which the arrows point.

Figure 5 is an enlarged fragmentary detail in 50 longitudinal section, illustrating the connection between the normally outer end of the outermost tubular member of the antenna mast and inner member thereof.

Figure 6 is a transverse section taken on the 55 line 6—6 of Figure 5, looking in the direction in which the arrows point.

Figure 7 is an enlarged fragmentary detail in 55 longitudinal section, illustrating the mounting of spring contact members upon the normally inner

end of the innermost of the tubular mast section members and the engagement of such means with the inner surface of the outermost of said tubular mast member.

Figure 8 is a transverse section taken on the line 8-8 of Figure 7, looking in the direction in which the arrows point, and

Figure 9 is an enlarged fragmentary detail in elevation showing the manner in which the normally inner end of the antenna mast rod is formed.

Having more particular reference to the drawings, the antenna mast comprises a tubular main member 1, a tubular secondary member 2 and a rod 3, capped or ended with a spherical element 4. The respective diameters of the members 1 and 2 are such that the former slidably receives the latter therein, while the diameter of the rod 3 is such that it, in turn, is slidably received in the secondary member 2, i. e., the member 2 and the rod 3 are, at times, telescopically engaged with each other and are each, at times, telescopically engaged or received within the main member 1. It is preferable that the length of the secondary member 2 be somewhat greater than the length of the main member 1, while the length of the rod 3 is greater than the length of the secondary member 2. Hence, when these constituent elements are in telescoped or collapsed positions, they will assume the relativity shown in Figures 1 and 2 of the drawings.

If desired, the tubular main and secondary members 1 and 2 may be made of hard brass tubing having their exterior surfaces plated or provided with other suitable finish. The rod 3, preferably, is constructed of stainless steel. Obviously, however, the materials from which the tubular main and secondary members 1 and 2 and the rod 3 are made, may be varied or changed, as conditions or preference may dictate.

The tubular main member 1 is adapted to be supportingly engaged or received within the socket portion of the usually vertically positioned tubular or sleeve-like mounting bracket, generally indicated by the numeral 5, the detailed construction and characteristics of which are described and claimed in my co-pending application Serial No. 596,126, filed May 28, 1945, now abandoned, and, to some extent, rather generally hereinafter described.

The normally outer end portion of the tubular main member 1 is annularly enlarged or expanded, as at 6, and its point of jointure with the body portion of said member provides an internal annular shoulder 7.

The tubular secondary member 2 is longitudinally slidably received within the main member 1 and has its normally outer end similarly annularly enlarged or expanded, as at 8, providing an internal annular shoulder 9 at its point of jointure with the body of said member.

In order that yieldable frictional connection shall be effected between the main member 1 and the secondary member 2, a spider spring, designated in its entirety by the numeral 10, is snugly received within the annularly enlarged or expanded portion 6 of the main member 1, resting or seating upon an annular washer 11 bearing or resting upon the internal annular shoulder 7. The basal portion of the spider spring 10 is, preferably, in the form of an annulus flushly engaging and seating upon the aforesaid washer 11 and having a plurality of relatively spaced, longitudinally disposed bowed or arcuately

formed arms 12 integral with and extended therefrom whereby to effect their relative positioning within the annularly enlarged portion 6 in the manner shown in Figure 6 of the drawings. The free or outer ends of the arms 12 terminate inwardly of the open outer end of the annular portion 6 of said main member and receive and support thereupon a second washer 13. A felt or fiber washer 14 is arranged within the outer open end portion of the enlarged annular portion 6, resting upon the adjacent side of the washer 13.

To maintain the element assembly designated by the numerals 10, 11, 13 and 14 in desired relationship within the annularly enlarged portion 6 of the main member 1 and to prevent longitudinal displacement thereof via its normally outer end, the outer end of the annular enlarged portion 6 is inturned or flanged, in a suitable manner, as indicated by the numeral 15, whereby the extremity thereof will be arranged in closed relationship to that portion of the secondary member 2 passing therethrough, as indicated in Figure 5 of the drawings.

The bowed or arcuate formations of the arms 12 of the spider spring 10 are such that they will normally have positive frictional engagement with adjacent portions of the outer surface of the secondary member 2, as it is received within the main member 1 and, at times, is slid, shifted or adjusted with relation thereto.

The annularly enlarged outer end portion 8 of the tubular secondary member 2 receives and supports therein, at its internal annular shoulder 9, a washer 16. A spring member 17 of substantially U-shaped cross-sectional formation and having its extremities arcuately formed or bowed, as well shown in Figure 4 of the drawings, is received within the annularly enlarged portion 8 of the secondary member 2 and has positive spring frictional engagement with the outer surfaces of a particularly adjacent portion of the rod 3. At this point, it may be noted that the width of cross-sectional area of the spring 17 is such that it has snug accommodation or reception within said annularly enlarged portion 8. A second washer 18 is engaged with the normally outer end of the spring 17 within the annularly enlarged portion 8 and has a felt or fiber washer 19 engaged with or bearing upon its outer side, said washers 18 and 19 receiving the rod 3 therethrough, as shown in Figures 2 and 3 of the drawings and the latter washer having physical engagement or contact with the rod, 50 for a purpose which will be hereinafter described.

To maintain the assembly of elements 16, 17, 18 and 19, in proper close and relatively longitudinally immovable relation within the annularly enlarged portion 8 of the secondary member 2, the outer or free end of the latter is inturned or flanged in the manner indicated by the numeral 20, permitting of sliding passage of the rod 3 therethrough.

In order that rattling or similar vibratory movement of the normally inner end portion of the secondary member 2, within the main member 1, will be prevented, cross-sectionally arcuately shaped spring arms 21 are provided to the inner end portion of the secondary member 2 and are correspondingly secured at certain of their ends to adjacent portions of the outer surface of said secondary member 2, by spot-welding, riveting, etc., as indicated at 22. These diametrically opposed spring arms 21, because of 70 their arcuate cross-sectional forms, have snug or

embracing engagement with adjacent portions of the secondary member 2 and, as will be noted upon reference to Figure 7, in particular, their inner ends or unsecured end portions diverge from adjacent portions of the secondary member 2, i. e., they are, in effect, relatively outwardly flared. Consequently, upon this divergent or flaring disposition of the free end portions of the spring arms 21, it will be noted that the same will have yieldable or spring frictional bearing engagement with adjacent portions of the inner surface of the main member 1, in the fashion well shown in Figure 7 of the accompanying drawings. Because of such engagement, effectual anti-rattling means will be accorded to the inner end portion of the secondary member 2 and particularly, to that portion of the same as shall be within the main member 1 at those times when the constituent elements of my improved antenna mast are in collapsed, distended or partially distended positions.

The hereinbefore described spring members 10, 11 and 21, as will be understood, effectually function to provide positive anti-rattling means to the constituent elements of the antenna mast. It is, moreover, of note that said spring members will function to movably retain or secure the secondary member 2 and the rod 3 of the antenna mast construction in any of their various relatively adjusted positions; also, that they will serve to effect and maintain constant and dependable electrical connection and conductivity between the members 1 and 2 and the rod 3.

My improved antenna mast, following assembly of its hereinbefore described constituent members, has a suitable quantity of grease or other lubricant injected or otherwise delivered into its telescopically interengaged main and secondary members 1 and 2, respectively. Following the injection of this lubricant supply, the normally inner or lower end of the tubular main member 1 is effectually closed by a metal plug 23, or its equivalent, having a screw threaded outwardly opening pocket 24 formed therein. The closure plug 23, of course, may be secured within the normally inner or lower end of the member 1 in various manners, though in the present embodiment, I choose to effect its securing by peening or indenting an adjacent portion of said member 1, as indicated at 25.

The grease or lubricant supplied to the interior of the tubular main and secondary members 1 and 2 will be brought into contact with the felt or fiber washers 14 and 19, hereinbefore described. In consequence, said washers will become saturated and, because of their frictional engagement or contact with the secondary member 2 and the rod 3, respectively, they will cause the surfaces of the same to have a covering film of protective grease or lubricant applied thinly and uniformly thereto and thereover, especially, at those times when the tubular secondary member 2 and/or the rod 3 is or are moved to their respective distended or partially distended positions. This thin film-like coating of grease or lubricant, obviously, will serve to protect the exposed surfaces of the secondary member 2 and the rod 3 from deterioration due to prolonged subjection to the elements or climatic conditions.

The rod 3, slidably received within the tubular secondary member 2, has its inner end portion, i. e., that portion thereof engaged within said member 2, obliquely bent or offset in the fashion shown in the Figures 2, 7 and 9 of the drawings. This obliquely offset portion of the rod will have

its free extremity bindingly or frictionally engaged with a portion of the inner side of the secondary member 2 and, accordingly, will be accorded means, in addition to the spring 17, whereby its secure anti-rattling though movable retention in any one of a number of longitudinally adjusted positions with relation to said member 2, will be assured. To prevent longitudinal displacement of the rod 3 from its receiving tubular secondary member 2, I may and preferably do effect an enlargement or shoulder portion 26 therein, by swaging, stamping or other well known methods, preferably, at a point somewhat in proximity to its oblique and normally inner end portion. Moreover, it will be noted that by reason of the forming of the enlargement or shoulder 26 in the rod 3, the obliquing of the inner end portion of the rod 3 will be facilitated.

To secure the improved antenna mast within its mounting bracket 5, aforesaid, a coupling or connecting screw 27 is engaged through the lower portion of the bracket mounting liner or lining material 28 and is turned into engagement with the screw-threaded pocket 24 formed in the closure plug 23.

Electrical conductivity between the improved antenna mast members engaged and supported in the mounting bracket 5 and the radio apparatus to which it is provided, is effected by means of a suitable lead-in conductor, indicated in its entirety by the numeral 29. One end of this lead-in is electrically connected to the radio apparatus (not shown). Its remaining end portion is securely engaged in and through a nipple 30 fixedly carried upon and extending from an appropriate and preferably lower portion of the bracket 5, as shown in Figures 1 and 2 of the drawings. The conductor per se, is passed into the bottom or lower portion of the bracket antenna mast receiving socket where it engages an apertured flat contact terminal 31 adjacent and engaging the lower end of the tubular main member 1 (see Figure 2). Positive mechanical and electrical connection of the terminal 31 to said member 1 is effected by the coupling screw 27 which passes through the aperture in the terminal 31 and thence, into screw-threaded engagement with the downwardly opening pocket 24 in the closure plug 23 of the main member 1.

To reinforce and protect the connection of the lead-in 29, just described, a sheathing of woven wire fabric 29' is, preferably, engaged over the latter throughout its length, and that portion thereof in proximity to the nipple 30, cappingly engages over the same and is secured thereto by soldering or other means. A tubular guard sleeve 32 of rubber or like material is engaged over the adjacent end portion of the lead-in 29 and its sheathing 29' and over the exterior of the nipple 30 for weather-proofing and similar purposes.

It is manifest that certain changes and/or modifications of the arrangements and constructions herein disclosed, are within the province of the teachings of the invention. I, therefore, do not intend that such disclosure shall or should be construed as limiting the ambit of my invention to any extent, save that as is within the scope of and the inventive spirit expressed by the hereto appended claim.

70 I claim:

An antenna mast, including telescopically engaged tubular members, a rod telescopically received in the innermost one of the tubular members, the normally outer end portion of said 75 innermost tubular member having a chamber

therein, and a member made of spring sheet-like material of substantially U-shaped cross-sectional formation received in said chamber and retained therein against relative longitudinal movement, the opposite side edges of said member having tensioned bearing on adjacent portions of the chamber walls, and the opposite sides of the member being outwardly transversely bowed throughout their respective lengths and having tensioned bearing on adjacent and opposite portions of said rod.
